United States Patent [19]

Casciotti et al.

[11] Patent Number: Des. 274,719

[45] Date of Patent: ** Jul. 17, 1984

[54] **MULTI TERMINAL ELECTRICAL CONNECTOR PLUG**

[75] Inventors: **Albert Casciotti, Hershey; Robert D. Hollyday, Elizabethtown**, both of Pa.

[73] Assignee: **AMP Incorporated, Harrisburg, Pa.**

[**] Term: **14 Years**

[21] Appl. No.: **378,036**

[22] Filed: **May 14, 1982**

[52] U.S. Cl. **D13/24**

[58] Field of Search ..... **D13/24; 339/91 R, 103 R, 339/126 R, 176 R, 176 M, 198 R, 198 GA, 217**

[57] **CLAIM**

The ornamental design for multi terminal electrical connector plug, as shown and described.

DESCRIPTION

FIG. 1 is a perspective view of the multi terminal electrical connector plug showing our new design;

FIG. 2 is a front elevation thereof;

FIG. 3 is an end elevation thereof;

FIG. 4 is a top plan view thereof;

FIG. 5 is a bottom plan view thereof; and

FIG. 6 is a rear elevation thereof.
